UNITED STATES PATENT OFFICE.

CHARLES J. MACARTHUR, OF NEWARK, NEW JERSEY.

MATRIX FOR THE PRODUCTION OF PRINTING-PLATES.

1,128,022.

Specification of Letters Patent.

Patented Feb. 9, 1915.

Application filed March 1, 1913. Serial No. 751,586.

To all whom it may concern:

Be it known that I, CHARLES J. MACARTHUR, a citizen of the United States, residing at Newark, in the county of Essex and State of New Jersey, have invented certain new and useful Improvements in Matrices for the Production of Printing-Plates, of which the following is a specification.

- 10 My present invention pertains to an improved matrix for the production of a printing plate, an improved plate for producing such matrices, and to the method or process of making the matrices and plate.
- 15 The invention has for its main object the formation of a matrix and a master plate, from which master plate any number of matrices may subsequently be produced, the printing plates in turn being produced from 20 the matrices thus formed. The printing face of said plates exhibits a finished surface having such relatively raised and depressed portions, sections or lines as are necessary and desirable to produce a picture 25 (or imprint) displaying solids, half-tones or middle lights, and high lights.

Stated in general terms, the process is carried out in the following manner: Upon the rear face of a copper plate, having upon 30 its front, say, a picture produced by any desired process, there is mounted a print or proof of such picture. Upon such print or proof there is mounted a suitable underlay, the sections where the solids in the ultimate 35 picture are to appear being built up to the greatest extent, somewhat lower for the half- or middle tones, and not at all for the high- light sections. A marginal strip, of a height equal to the highest point in the underlay, or make-ready, will also be placed 40 all around the plate upon its back, adjacent its edge, forming a continuous strip or band. The built-up marginal portion or strip may be termed a controlling bearer, 45 and serves to prevent the plate from tilting, when subjected to pressure against a lead sheet, as would otherwise sometimes occur, owing to the different gradations in the underlay beneath the different portions or sections 50 of the plate, and particularly where they are materially thicker at one end of the plate than at the other. The face of the plate preferably has formed in it, adjacent its edge, but within the confines of said strip or band, a groove or channel. It is conceivable 55 and, in fact, found entirely practicable

in practice to employ separate strips of a thickness exactly equal to the thickness of the plate adjacent the ends and sides of the plate, instead of building up the underlay around the margin of the plate, as just described, and to secure to such strips of underlay equal in thickness to the greatest height or thickness of the underlay applied to the plate. Or strips of a thickness equal to the conjoint thickness of the plate and the maximum thickness of the underlay may be used as the controlling bearers. The plate thus treated and provided with the controlling bearer, however formed, has superposed upon it a lead sheet and the two are then placed within a suitable press and subjected to pressure. Such pressure tends to deform the copper plate, forcing out those portions upon which the make-ready or underlay has been placed and likewise the margin of the plate beneath the controlling bearer or bearers aforesaid. Naturally, the lead in the plate will likewise be displaced or caused to flow, thereby producing in such lead plate an intaglio of the plate, or a matrix having the exact design in every particular displayed by the plate. Such matrix is employed to produce, preferably by electro-deposition, the face of the printing-plate. The face will, of course, be backed by suitable metal and planed to plate-thickness. The copper plate formed during the above steps may be employed to produce other 90 matrices, or if desired be used as a printing surface.

In order that the invention may be readily understood in all the steps, a detailed description will be given, reference being had to the annexed drawings, wherein:

Figure 1 is a face view, of the original copper plate, having the picture appearing thereon; Fig. 2 a sectional view, on the line 2—2 of Fig. 1; Fig. 3 a rear view of the plate with the underlay or make-ready applied thereto; Fig. 4 a sectional view, on the line 4—4 of Fig. 2; Fig. 5 a sectional view, showing the plate with its attached underlay or make-ready and the matrix sheet positioned upon the press-bed; Fig. 6 a similar view illustrating the action which takes place after the parts have been subjected to pressure; Fig. 7 a sectional view of the completed matrix; Fig. 8 a like view of the original copper plate; Fig. 9 a sectional view of a backed plate produced from the

matrix; and Fig. 10 a sectional view of the finished plate.

It will, of course, be understood that in the various sectional views the parts are considerably enlarged, this being necessary in order to fully illustrate the invention.

In the drawings, 1 denotes the original copper plate, having produced thereon a picture or design by any desired process. A 10 continuous groove or channel 2 is formed in the face of the plate, a slight distance from its edge, producing a rim 3. Upon the rear of the plate there will be secured a sheet 4, having imprinted thereon a duplicate of 15 the picture which appears upon the face of the plate, said imprint serving as a guide or index for the proper positioning of the make-ready or underlay. Such imprint should be of the same size as the plate, showing 20 a printed band where the rim 3 appears. Around the margin of the plate, over the rim 3, there will be placed a number of superposed pieces as 5, 6 and 7, equal in height to the highest point of the underlay or make-ready, which is placed upon the picture or design. One piece of such underlay is designated by 8, and in Fig. 3, is shown as provided with a series of vertical slits 9, which when the plate is pressed into the lead to 25 produce the matrix, will permit those portions of the plate which are beneath the same to remain in their normal plane, or in other words, such sections will not be pressed forward into the lead. Such unpressed or 30 unprotruded sections will, of course, print or appear as high lights in the ultimate picture as, for instance, the vertically-disposed blanks or lines 10, Fig. 1.

Superposed upon sheet 8 is an underlay 40 11, having slits 12 cut therein, see Fig. 3, which act to produce the high-lights in the drapery of the skirt. An additional underlay 13 may be placed over the shoulder and arm of the figure, and provided with cut- 45 away portions, as at 14 and 15, which openings may or may not, as desired, extend down through the underlay 11. Relatively heavy underlays will be provided at the top of the head, as at 16, and so with the arms, 50 while the part where the shadow of the arms falls will have an underlay of less height. So, too, any portion of the plate which is to be thrown forward will be backed up, as will be readily understood by 55 those skilled in the art, the high-light portions being unbacked. By the use of the printed band appearing on the sheet 4 the designer is enabled to employ the same as a means for securing correct registry of the 60 underlay. The plate thus built up is placed upon a fixed unyielding bed or platen of a press, such as an "Albert" press, with the underlay resting upon the platen. There is then placed upon the copper plate a sheet 65 of lead 17, and the whole subjected to pres-

sure, which has the effect of deforming the copper plate in the manner shown in Fig. 6, and at the same time producing in the adjacent face of the lead plate an exact intaglio of the face of the copper plate. Said lead plate 17, which in fact is the matrix, is shown in Fig. 7, while the copper plate 1 is shown in Fig. 8, stripped of all its underlay. As before noted, underlays 5, 6 and 7 are of a height equal to the highest portion of any other underlay on the plate and when the plate is subjected to pressure the outer marginal section or rim 3 is thrown upwardly and acts as a stop or limit to the action of the pressure, said rim, as will be noted upon an inspection of Fig. 8, standing as high as any other portion of the plate. In other words, the rim becomes a bearer and controls the height to which any other portion of the plate may be pushed forward. 75 From the matrix a printing plate is produced. The skin 18, Figs. 9 and 10, of such plate is preferably formed by electro-deposition of any suitable substance upon the face of the matrix, said skin being subsequently 80 backed with electrotypers' metal 19 and planed off, as is usual, the finished plate being shown in Fig. 10. As will be noted, the plate presents a surface in which those parts which are to print solid stand the highest, 85 the half-tone sections somewhat lower, and the high-light the lowest of all. Any number of matrices may be produced from the original copper plate with its attached underlays. 90

It is, of course, to be understood that the annexed drawings are merely illustrative and that any design, no matter how fine, may be reproduced in the matrix, with the various portions of the design thrown into 105 the proper and desired relief, according to the dictates of the designer.

At noted at the outset, it is not essential that the controlling bearer (or bearers) be formed as an integral portion of the plate, 110 for such bearers may be separately formed, and in fact used with plates which have been previously formed and from which the margin has been trimmed off. Such separate strips of metal are placed around the plate and are, of course, of a thickness exactly equal to that of the plate itself, or of the plate with its maximum number of attached underlays. A matrix produced in 115 lead from the plate and controlling bearer strips will show the impression of these bearer strips, and when the copper is deposited on the face of the matrix it will likewise be deposited upon or in the depressions formed by the strips; consequently, the copper plate thus produced will have a margin around the same of a height equal to the highest point on the plate. This margin then acts as a protector for the completed plate when the back is being planed. 120

off, holding the plate level and to a certain extent controlling the depth to which the planing knife will cut. After the plate is thus finished, the extra metal around the 5 margin is trimmed away.

In practice it has been found that plates produced by the use of the controlling bearer, be it continuous or formed in sections, are of uniform height and will print 10 uniformly, so that the employment of overlays or packing for the form is unnecessary.

Having thus described my invention, what I claim is:

1. A matrix from which a printing-plate 15 may be produced, comprising a body of metal having impressed in and upon its surface the design desired to be reproduced, with those portions of the design which are to print solid, in half-tone, and in high- 20 light in the plate to be produced from the matrix impressed proportionately deeper, from a greater to a less extent.

2. A matrix from which a printing-plate 25 may be produced, comprising a body of metal having impressed in and upon its surface by pressure and consequent displacement or "flow" of the metal, the design desired to be reproduced, the displacement being deepest where that portion of the 30 plate to be formed prints solid, and less deep where it prints half-tones.

3. As a new article of manufacture, a matrix from which a printing-plate may be 35 produced formed of metal which will flow under pressure and having impressed in its face an intaglio of the design to be reproduced, said intaglio having graded depths.

4. As a new article of manufacture, a matrix from which a printing plate may be 40 produced, said matrix being made of a metal which will flow under pressure and having impressed in its face an intaglio of the design to be reproduced, said intaglio having graded depths, the matrix likewise having 45 depressions formed adjacent its edges of a depth substantially equal to the depth of the greatest depression in the intaglio design.

5. The process of producing a matrix for 50 the production of a printing-plate, which consists in backing up a plate having a design upon its printing surface, with underlays of differing heights; imposing a body of yielding metal against the design face 55 of the plate; and finally subjecting the parts to pressure and thereby causing those portions of the face of the plate which are backed by the overlay to be protruded or thrown forwardly out of the primary plane 60 of the plate, and simultaneously force such protruded portions into the face of the body of metal, whereby an intaglio of the newly-formed face of the plate will be produced in the body of yielding metal.

6. The process of producing a matrix for

the production of a printing-plate, which consists in forming a groove or channel adjacent to the edge of a plate and upon that face which has the design or picture produced thereon; securing upon the rear face 70 of the plate a print of such design; mounting a "make-ready" or "underlay" upon such print and at such points or places as it is designed to protrude the face of the plate to produce "solids" and "half-tones", 75 the underlay being highest over the "solids"; likewise mounting around the edge of the print and over the marginal portion of the plate a make-ready of a height equal or substantially equal to the highest 80 point in the make-ready positioned on the body of the print; imposing the face of the plate upon a body of metal which will "flow" under pressure; and finally subjecting the parts to pressure, and thereby causing those portions of the face of the plate which are backed by the underlay to be protruded or thrown forwardly out of the primary plane of the plate, and also causing the margin of the plate to be likewise protruded, and simultaneously force such protruded portions into the face of the body of metal, whereby an intaglio of the newly-formed face of the plate will be produced 90 in the body of yielding metal. 95

7. The process of producing a matrix for the production of a printing-plate, which consists in placing the design face of a plain-back plate against a body of metal which will "flow" under pressure, and forcing the 100 plate against such body to produce an intaglio of the design and likewise subjecting certain predetermined portions of the back of the plate to such pressure as will deform or protrude such portions of the face of the plate beyond the normal plane of the face and force such protruded portions correspondingly deeper into the body of metal. 105

8. The process of producing a matrix for the production of a printing-plate, which 110 consists in placing the design face of a plate of metal having a plain back and a design face against a body of metal which will flow under pressure, the design lying next to the body; impressing the design as 115 a whole into said body; and likewise protruding or projecting those portions of the plate which should print solid and in half-tones forwardly beyond the normal plane of the face of the plate and correspondingly deeper into the body of metal. 120

9. The process of producing a matrix for the production of a printing-plate, which 125 consists in forming a groove adjacent to the edge of a plate of metal and upon that face thereof which bears the design to be reproduced; imposing such face upon a body of metal which will flow under pressure; placing an underlay upon the back of the plate over those portions of the design where the 130

face of the plate is to be protruded; placing an underlay under the rim portion of the plate formed by the groove, said underlay being of a height equal or substantially equal to the highest portion of the design underlay; and finally subjecting the parts to pressure.

10. The process of producing a matrix for the formation of a printing-plate, which 10 consists in forming a "bearer" rim around a plate having a design upon its face; imposing said plate upon a body of metal which will "flow" under pressure; and finally protruding said rim, and those portions of the design which are to print solid and in half-tone, into said body, the rim being protruded to an extent equal or substantially so to the greatest protrusion of any other portion of the plate.

20. 11. The process of producing a matrix for the formation of a printing-plate, which consists in placing a plate of metal having a design thereon against a body of metal which will flow under pressure, the design 25 lying next to the body; impressing the design into said body and likewise protruding or projecting those portions of the plate which should print solid and in half-tones forwardly beyond the normal face of the 30 plate and correspondingly deeper into the body of metal; and simultaneously protruding a rim adjacent the edge of the plate of a height equal or substantially equal to the highest protruded portion of the body of 35 the plate.

12. The process of producing a plate for the production of matrices from which similar printing-plates may be formed, which 40 consists in placing upon the back of a plate having a design upon its face an underlay, or make-ready conforming in outline to the parts which are to be forced outwardly; forming a controlling bearer around the plate, said bearer being of a thickness equal 45 or substantially so to the greatest thickness of the underlay; imposing against the design face of the plate and the controlling bearer a body of metal which will flow under pressure; and finally subjecting the 50 parts to pressure.

13. The process of producing a plate for the production of matrices from which similar printing-plates may be formed, which 55 consists in placing upon the back of a plate having a design upon the face an underlay, or make-ready conforming in outline to the parts which are to be forced outwardly; forming a controlling or bearer rim around

the margin of said plate, said rim being of a thickness equal or substantially so to the 60 joint thickness of the plate and the maximum underlay; imposing against the design face of the plate and the rim a body of metal which will flow under pressure; and finally subjecting the parts to pressure. 65

14. The process of producing a matrix for the formation of printing-plates, which consists in forcing or protruding the face of a plate having a picture or design thereon, and a rim or controlling bearer surrounding 70 said picture, into a body of metal which will flow under pressure, the rim being evenly projected or protruded throughout and to an extent equal or substantially so to the greatest protrusion effected by the 75 face of the plate.

15. The process of producing a matrix for the formation of printing-plates, which consists in forcing to graded depths, the 80 face of a plate having a picture or design thereon, and likewise forcing a rim or controlling bearer surrounding the picture, into a body of metal which will flow under pressure, the rim being evenly projected 85 throughout into the metal and to an extent equal or substantially so to the greatest protrusion effected by the face of the plate.

16. The process of producing a matrix for the formation of printing-plates, which consists in forcing as a whole the face of a 90 plate having a picture or design thereon, and certain selected portions of said face to a greater extent than others, into a body of metal which will flow under pressure, and simultaneously therewith forcing a rim or 95 controlling bearer surrounding the picture into the metal body to an extent equal or substantially so to the greatest protrusion effected by the face of the plate.

17. The process of producing a matrix 100 for the formation of a printing-plate, which consists in forming a "bearer" rim upon a plate having a design upon its face; imposing said plate upon a body of metal which will "flow" under pressure; and finally 105 protruding said rim and those portions of the design which are to print solid and in half-tone into said body.

In testimony whereof I have signed my name to this specification in the presence of 110 two subscribing witnesses.

CHARLES J. MACARTHUR.
